(57) **CLAIM**

The ornamental design for a dual carrier for spreaders, as shown and described.

DESCRIPTION

FIG. 1 is a perspective view of a dual carrier for spreaders showing my new design;

FIG. 2 is a top plan view of the carrier of FIG. 1;

FIG. 3 is a bottom plan view of the carrier of FIG. 1;

FIG. 4 is a front elevational view of the carrier of FIG. 1;

FIG. 5 is a rear elevational view of the carrier of FIG. 1;

FIG. 6 is a left side elevational view of the carrier of FIG. 1;

FIG. 7 is a right side elevational view of the carrier of FIG. 1; and,

FIG. 8 is an alternate perspective view showing the carrier of FIG. 1 in use.

The portions shown in broken lines are included for illustrative purposes only and form no part of the claimed designs.
